UNITED STATES PATENT OFFICE

2,562,997

FLASHLIGHT OIL TESTER

Leon G. Alexander, Charlotte, and James W. Sherrill, Belmont, N. C., assignors to Wix Accessories Corporation, Gastonia, N. C., a corporation of North Carolina

Application November 5, 1947, Serial No. 784,212

3 Claims. (Cl. 88—14)

1

The invention relates to a flashlight oil tester for testing and comparing fluids, such as oil and the like, and provides an illuminated fluid testing means for visually inspecting oil and the like for fluidity and pollution.

An object of the present invention is to provide a simple, practical and comparatively inexpensive unit adapted to be readily applied to a flashlight such as a regular Boy Scout Army type, without necessitating any change or alteration in the construction of the flashlight and capable of enabling the quick visual checking of the clarity of used crank case oil by service station attendants and others and a simultaneous comparison of a sample of such used oil with clean unused oil while both the sample of used oil and the clean unused oil are simultaneously illuminated by a regular flashlight battery bulb.

A further object of the invention is to provide for use with an ordinary or standard flashlight a unit which may be easily and quickly applied to the same without necessitating any change or alteration in the construction of the flashlight and which may be equipped with one or more chambers or receptacles for holding a plurality of types of oil or other liquids and which is also equipped with a plain transparent lens or window adapted to serve as a spotlight for use by an attendant or others at night as well as forming a dish or receptacle for holding a sample of dirty or used oil obtained from the crank case of an internal combustion engine of an automobile or other automotive vehicle by the ordinary oil level dip stick with which such internal combustion engines are usually equipped.

It is also an object of the invention to provide a flashlight receiving unit forming a transparent, translucent or opaque wall in front of the outer end of the flashlight and adapted to have advertising matter applied to it by lithographing or other means for advertising various articles or commodities.

It is also an object of the invention to provide a unit having an adapter adapted to fit over the original flashlight lens or a lens holding cap or the like, without any change or alteration in the construction of the flashlight so that the latter may be easily serviced by practically any service station in the country for renewal of batteries, bulbs, or even switch and body.

With the above and other objects in view, the invention consists in the construction and novel combination and arrangement of parts herein-after fully described, illustrated in the accompanying drawings and pointed out in the claims:

2

hereto appended, it being understood that various changes in the form, proportions, and minor details of construction, within the scope of the claims, may be resorted to without departing from the spirit or sacrificing any of the advantages of the invention.

In the drawings:

Fig. 1 is a front elevation of a flashlight unit constructed in accordance with this invention;

10 Fig. 2 is a vertical longitudinal sectional view of the same and a portion of the Boy Scout Army type flashlight, taken substantially on the line 2—2 of Fig. 1;

Fig. 3 is a transverse sectional view of the flashlight unit taken substantially on the line 3—3 of Fig. 1, parts of the flashlight shown in Fig. 2 being omitted for convenience of illustration;

Fig. 4 is a front elevation of a flashlight unit illustrating another form of the invention;

15 Fig. 5 is a transverse sectional view of the same taken substantially on the line 5—5 of Fig. 4;

Fig. 6 is a vertical sectional view taken substantially on the line 6—6 of Fig. 4; and

20 Fig. 7 is a transverse sectional view taken substantially on the line 7—7 of Fig. 4.

Referring particularly to Figs. 1 to 3, inclusive, of the accompanying drawings in which is illustrated one form of the invention, 1 designates an adapter preferably constructed of sheet metal but any other suitable material may, of course, be employed in the construction of the adapter. The adapter, which is tapered and flared outwardly, is provided at its inner end with

25 an annular socket 2 which fits over the plastic lens 3 of a Boy Scout Army type flashlight 4. The flashlight lens 3, which is transparent, may be constructed of any suitable material and when the adapter is made of sheet metal the inner

30 or smaller end of the adapter may be extended and spun over the plastic flashlight lens 3. The annular socket 2 may be constructed in any other manner and, when permanently attached to the plastic flashlight lens 3, may be removed from

35 the flashlight with the flashlight lens. The socket 2 may frictionally engage the plastic flashlight lens 3 and may be placed on and removed from the flashlight with or without removing the flashlight lens 3. By this construction the

40 flashlight unit may be readily applied to an ordinary flashlight without any change or alteration in the construction thereof and the flashlight may be easily serviced by practically any service station in the country for renewal of batteries,

45 bulbs, or even switch and body.

50

The annular socket 2 is constricted adjacent the inner smaller end of the adapter to provide a shoulder 5 which fits against the outer face of the plastic lens 3 of the flashlight 4 and the edge of the socket 2 may be extended inwardly to provide an annular flange 6 for engaging the edge of the cylindrical portion 7 of the plastic flashlight lens 3 which is firmly held between the shoulder 5 and the flange 6. By this construction the oil testing unit is rigidly mounted on the flashlight at the front end thereof so that when the circuit of the flashlight is closed in the usual manner and rays of light from the flashlight bulb are caused to pass through the flashlight lens 3, the oil testing unit will be illuminated.

The flashlight 4 is of the ordinary construction and further description thereof is unnecessary.

The adapter 1 is provided at its outer or larger end with an outwardly extending annular flange 9 which fits within an annular groove 10 in the inner periphery of an elastic retaining ring 11 of neoprene or other suitable material, which constitutes a rounded rim at the outer end of the adapter. The annular groove 10 also receives the peripheral edge 12 of a plastic disc 13 which may be transparent, translucent or opaque and which may be constructed of any other suitable material. The plastic disc 13 is provided with three substantially concavo-convex depressions 14, 15 and 16 but the number of depressions may, of course, be varied, as will be readily understood. Annular seats or recesses 17 and 18 are provided around the depressions 14 and 15 and flat transparent plastic discs 19 and 20 are secured in the said seats to form with the depressions 14 and 15 containers or receptacles 21 and 22 for the reception of samples of pure light and heavy oils, and the depression 16 is transparent and is adapted to receive a sample of dirty or used oil obtained from the crank case of an engine of an automobile or other automotive vehicle by oil level dip stick in the usual manner, so that a sample of used oil may be simultaneously compared with a sample of pure unused oil when the circuit of the flashlight is closed and rays of light from the flashlight bulb are caused to pass through the lens 3 of the flashlight. This will illuminate the oil testing unit and also will render visible advertising matter placed on the disc 13 and surrounding the containers and the depression 16. The depression 16 is adapted to constitute a combined sample holding and spotlight area for enabling a flashlight equipped with an oil testing unit to be used for purposes other than testing oil. For instance, it will enable the oil level dip stick to be readily located at night without liability of the hand of the operator coming in contact with the hot portion of the motor. When the depression 16 is held in a horizontal position facing upwardly it forms a dish and is adapted to receive and hold a sample of used or crank-case oil and as it is arranged in side by side relation with the containers 21 and 22, it is adapted to be illuminated simultaneously with said containers by the bulb of the flashlight so that a comparison of used or crank-case oil may be made with clean oil contained within the containers or receptacles 21 and 22 for determining whether or not a change of oil is necessary.

In Figs. 4 to 7, inclusive, is illustrated another form of the invention in which an adapter 23 is employed for mounting on the plastic lens of a

flashlight an oil testing unit having two plates 24 and 25 of metal, plastic, or any other suitable material, provided with three flanged circular openings 26, 27 and 28 and constructed substantially the same as the metal plates of the oil testing unit shown, described and claimed in a pending application filed by us on or about August 27, 1947, Serial No. 770,776. The flanged peripheral portions of the plates 24 and 25 at the openings form grooves 29, 30 and 31. The grooves 29 and 30 receive the peripheries of transparent containers or receptacles 32 and 33 formed by clear transparent concavo-convex discs 34 and 35 of glass, plastic or other suitable material. The concavo-convex discs which are secured together at their peripheries form the said receptacles 32 and 33 and are adapted to contain samples of pure light and heavy oils or other liquids. The groove 31 at the other opening 28 receives a single inverted concavo-convex lens 36 of glass, plastic or other suitable material presenting a dished exterior face adapted to receive a sample of used oil from a crank case for enabling the same to be compared with the contents of one or the other of the receptacles 32 and 33 which are simultaneously illuminated with the sample of used oil when the circuit of the flashlight is closed.

The adapter 23 is provided at its outer enlarged end with an annular flange 37 forming a ledge to receive the outer peripheral portions of the plates 24 and 25 which are retained on the ledge by a metal rim 38 approximately L-shaped in cross section and designed to be secured to the adapter by any suitable means.

The annular rim extends over the periphery of the outer plate 24 and securely retains the two plates 24 and 25 on the ledge 37 of the adapter. The inner reduced end of the adapter is constructed the same as the adapter 1, heretofore described.

The hollow tubular adapter has opaque walls to prevent rays of light from the flashlight lens from spreading laterally beyond the area of the oil testing unit at the inner face thereof and the adapter may be varied in form, as will be readily understood.

We claim:

1. For use with a flashlight, a liquid tester unit provided with a transparent receptacle for containing clean liquid and having a transparent area which when held in a horizontal position is adapted to receive a sample of a liquid to be tested, and a tapered outwardly flared tubular adapter having opaque walls and provided at its inner end with means for securing it to the exterior of a flashlight at the front end thereof over the flashlight lens, said adapter being provided at its outer end with an annular ledge receiving the liquid tester unit and supporting the same in front of and spaced from the flashlight lens and an elastic rim surrounding the liquid tester and the ledge of the adapter and having an annular groove receiving said ledge and the liquid tester unit for securing the latter to the adapter, whereby the liquid receptacle and the transparent area may be simultaneously illuminated by the flashlight bulb for testing a sample of used or crank-case oil and may be wiped clean to recondition the transparent area for further testing operations.

2. For use with a flashlight, a tubular adapter provided at its inner end with means for mounting it on the exterior of a flashlight at the front end thereof over the lens of the flashlight, and

a liquid tester unit supported by the adapter in front of and spaced from the lens of the flashlight and comprising a disc of plastic material provided with approximately circular transparent depressions and a transparent disc secured over one of the depressions and cooperating with the same to form a sealed receptacle for a clean liquid, another of said depressions forming an open exterior receptacle adapted when held in a horizontal position facing upwardly to receive 10 a sample of a liquid to be tested, whereby the liquid to be tested and the clean sample may be simultaneously illuminated by the flashlight and after testing said open exterior receptacle may be wiped clean and reconditioned for further testing operations.

3. For use with a flashlight, a liquid tester unit provided with a transparent receptacle for containing clean liquid and having an exterior transparent area adapted when held in a horizontal 20 position to receive a sample of a liquid to be tested, and a tapered outwardly flared tubular adapter having opaque walls and provided at its inner end with means for securing it to the exterior of a flashlight at the front end thereof adjacent the flashlight lens, said adapter being provided at its outer end with an annular ledge receiving the liquid tester unit, and an elastic rim

surrounding the liquid tester unit and the ledge of the adapter and securing the liquid tester unit to the adapter whereby the liquid receptacle and the transparent area may be simultaneously illuminated by the flashlight bulb for testing a sample of used or crank case oil and the transparent area may be wiped clean to recondition the same for a further testing operation.
